CHARLES H. CROSBY, OF BOSTON, MASSACHUSETTS, ASSIGNOR TO
HIMSELF, JOHN ROSS, AND CHARLES A. TROWBRIDGE.

Letters Patent No. 85,794, dated January 12, 1869.

IMPROVED BOLT-FASTENING FOR RAIL-TIES.

The Schedule referred to in these Letters Patent and making part of the same.

To all whom it may concern:

Be it known that I, CHARLES H. CROSBY, of Boston, in the county of Suffolk, and State of Massachusetts, have invented a new and useful Improvement in Joints or Connections for Railway-Rails; and I do hereby declare that the following is a full, clear, and exact description thereof, which will enable others skilled in the art to make and use the same, reference being had to the accompanying drawings, forming part of this specification, in which—

Figure 1 is a plan or top view of my invention.

Figure 2 is a transverse section of the same, taken in the line $z z$, fig. 1.

Similar letters of reference indicate like parts.

This invention relates to a new and useful improvement in that class of joints or connections for railway-rails, in which screw-bolts pass transversely through plates placed at both sides of the rails, and also through the rails.

The object of the invention is to dispense with the use of nuts on the bolts, and to obtain a simple means for preventing the casual loosening and unscrewing of the bolts, the advantages of which will be hereinafter set forth.

In the accompanying sheet of drawings—

A A represent the ends of two railway-rails, which are placed nearly in contact with each other, a short space being allowed for expansion, and

B B' represent two plates, which are placed, one at each side of the rails, against the necks of the same.

These plates are perforated with holes, and also the rails A A, to admit of screw-bolts C passing through them, (see fig. 2,) the holes of the plate B', which is at the inner side of the rails, being tapped or provided with a female screw-thread, to receive the male screws of

the bolt C. The holes of the plate B, at the outer sides of the rails, are not tapped, neither are the holes in the rails.

Washers a are interposed between the plate B and the heads b of the bolts, and the heads b have each a hole made through them, to admit of a rod, D, being passed through all the bolt-heads. The ends of this rod are bent, in order to prevent it being casually withdrawn.

The object of the rod D is to prevent the casual turning of the bolts C, and the consequent loosening of the plates B B'.

By this arrangement, I dispense with the use of nuts entirely, the tapped holes in the inner plate B' answering the purpose of nuts, while the rod D, passing through the bolt-heads, effectually prevents the casual turning and unscrewing of the bolts.

The nuts of the ordinary screw-bolts used with rail-joints, are at the outer sides of the rails, and the heads, which are at the inner sides, are frequently broken off by the flanges of the car-wheels, causing a great deal of annoyance, and a considerable expenditure of time in replacing bolts—a difficulty which is fully obviated by my invention.

Having thus described my invention,

I claim as new, and desire to secure by Letters Patent—

The construction and arrangement of the perforated bolt-heads C, to admit of the passage through them of the rod D, substantially as described, for the purpose specified.

CHAS. H. CROSBY.
